UNITED STATES PATENT OFFICE.

JAMES POWERS, OF NEW YORK, N. Y., ASSIGNOR TO POWERS ACCOUNTING MACHINE COMPANY, OF NEW YORK, N. Y., A CORPORATION OF DELAWARE.

PRINTER-TABULATOR.

1,245,503.

Specification of Letters Patent.

Patented Nov. 6, 1917.

Application filed June 27, 1914. Serial No. 847,581.

To all whom it may concern:

Be it known that I, JAMES POWERS, a citizen of the United States, residing in New York city, in the county of New York and

5 State of New York, have invented certain new and useful Improvements in Printer-Tabulators, of which the following is a specification.

My present invention is an improvement 10 upon the printing tabulators in my pending applications, Serial No. 760,609 of April 12, and 802,363 of Nov. 22, 1913. It simplifies and reduces the number of parts of such machines and their cost, wear and liability 15 to derangement and thereby facilitates and cheapens their manufacture and up-keep, extends their usefulness and makes them more constant and reliable in service.

For uniformity and convenience, in this 20 application, reference characters generally refer to parts like, or having functions like, those so designated in pending application, Serial No. 802,363, hereinafter referred to as "the prior disclosure."

25 I provide frame and power transmission members generally like those of the prior disclosure, as follows: a bedplate raised by legs to a convenient height; mounted thereon a main frame; thereon an action frame; 30 on the bed plate a motor, gear case and transmission; in the main frame a main shaft and fixed thereto a pin-box, picker, work-suspending and action cams and, of novel construction and functions, pairs of selector- 35 retractor and justifying cams.

One of the main objects of the present invention is to provide an accounting machine having a plurality of groups of actions, of which one group may be devoted to designation 40 characters, others to list data and take totals called sub-totals individually of the several lists or groups of data, and still others to take grand-totals of a plurality of the lists of data.

45 Another object of the invention is to provide an arrangement whereby the means for selecting the setting pins of the listing actions may be interrupted while the listing actions are actuated to take totals.

50 Still another object of the invention is to provide means whereby certain of the groups may be maintained out of printing operation for an interval, while other groups are permitted to print, or all of the groups

maintained out of printing operation, and 55 all or only some of them permitted to print totals after a series of data has been accumulated.

A further object of the invention is to provide a mechanical card controlled work sus- 60 pending mechanism.

Still another object of the invention is to provide means whereby the sub-totals and grand-totals may be repeated.

A particular feature of the invention is the 65 provision of a novel means whereby all of the actions in printing operation may be accurately positioned to print an even row of figures.

These and other features, capabilities and 70 advantages of the invention will appear from the subjoined detailed description of one specific embodiment thereof illustrated in the accompanying drawings.

In the drawings, Figure 1 is a section parallel with the feed axis on the stepped planes 1—1 of Fig. 2, Fig. 2 is an anterior elevation with the frames and cover broken to show the actions. Fig. 3 is a plan and Figs. 4 and 5, respectively, an anterior and a side 75 elevation of the selector-synchronizing gearing. Figs. 6 to 10 inclusive illustrate the timer and selective controller in their operative relations with function-initiating, timing and controlling members, Fig. 6 being a 80 partial plan of a designating-group bay, Fig. 7 a partial side view corresponding thereto and with Fig. 1, Fig. 7^a a detail of the "total" key, Fig. 8 a corresponding anterior end view, Fig. 9 a similar, general, 85 small-scale elevation illustrating the action-bay arrangement, and Fig. 10 a corresponding sectional elevation on line 10—10 of Figs. 2 and 9. Fig. 11 illustrates the selective controller. Fig. 12 is a plan and Figs. 95 13 and 14 side and posterior elevations of a card hopper cheek plate. Figs. 15 and 16 are respectively lateral and transverse views of the hand-drive interpolator. Figs. 17, 18 and 19 illustrate the selector-retractor and 100 justifier, Figs. 17 and 18 being side elevations, with certain parts in section and Fig. 19 a transverse section on line 19—19 of Figs. 1 and 17. Fig. 20 illustrates a type of compensating selector-head.

I provide, but do not illustrate, a gear case, electric motor and transmission substantially like those, respectively designated

105

1, 1^e, M and 2 in the prior disclosure and, incompletely but sufficiently illustrated in Figs. 1, 2 and 19, a bed plate 1 and main frame 1^b, a main shaft 3 and thereon the feed-roll driving gear 3^c, and, within the main frame 1^b, a central picker cam 3^d, (the picker which it is adapted to operate not being shown,) a symmetrically-spaced pair of pin-box cams 3^e and a work-suspending cam 3^f; 5 and without said frame (Figs. 15 and 16) an action cam 3^f; and add pairs of selector-retractor cams 3^g and justifier cams 3^h (Figs. 10, 17, 18 and 19).

Interpolated between the transmission 15 and the main shaft, and operably connected with the work-suspending cam 3^f, and with a work-control pin 6^u (Fig. 2), is a card-controlled work-suspending mechanism 6, hereinafter fully described.

20 Fixed on the main frame 1^b, bisected by the axis of the machine and spaced to form a cardway, are upper and lower card-plates, respectively, 1^m, 1ⁿ, (Figs. 1 and 2,) which are drilled with a plurality of registering 25 holes corresponding with the record point series (except the "9's") of record cards. On the upper plate 1^m is a shoulder or stop 190 to stop the selectors S for any "9" punched in a card. To one side of the card- 30 plates is a novel, jointed card hopper 1^h (Figs. 1, 12, 13 and 14) located on the main axis above an opening in the main frame, and comprising end throat-channel stumps 1ⁱ integral therewith, whose posterior flanges 35 are flared to form a converging throat; fixed to said stumps a gage blade 1^j to limit the feed to one card per cycle; and posteriorly hinged to said stumps, end L-plates 10ⁱ, whose transverse legs rest on and are flush 40 with the gage blade and which can be swung back to give convenient access to the mechanism. To the other side of the card plates is a card bin (not shown) substantially like that of the prior disclosure.

45 Card feed mechanism, generally indicated by 4 (Fig. 1), and of which only the bearings of the feed rollers are illustrated, connected the hopper, the card-plates and the bin, and comprises a card picker and feed 50 rolls (not shown) which are in no wise novel.

The pin box 5 is made, mounted and reciprocated (from the cams 3^e) and its analyzing control pins 5^h and stop control pin 6^u 55 are mounted spring-extended and operate substantially as in the prior disclosure. When a card is functioning between the card plates 1^m, 1ⁿ and the pin box 5 is raised, arrested control pins 5^h, 6^u, become non-functioning. When the stop-control pin 6^u 60 passes a card or through a hole, it initiates the operation of the work-suspending mechanism 6. In complete cycles, such analyzing control pins 5^h as find holes in the card 65 extend their tips above the upper card plate

1^m and there reproduce the card record to position tabulating printing actions 7 to reproduce the controlling record in print and add and carry it in adders 8.

70 Work suspender, 6.

This being subject matter for a separate application is indicated in the drawings only by its stop control pin 6^u, shift box 6^x, bell crank 6^p and the roller 6^r thereof en- 75 gaging the cam 3^f; and its hand-rod 6^m.

As in the prior disclosure an action rock shaft 3^A mounted transversely in the action frame 1^c, (Figs. 15 and 16,) is operably connected with the action cam 3^f. This connection comprises, pivoted on the main frame, a bell-crank 3^u whose short arm mounts a roller 3^v engaged with said slot cam 3^f, and whose other arm terminates in an adjustable head 3^w. On the action shaft 85 3^A is a rock arm 3^D.

Figs. 15 and 16 illustrate the action shaft arm 3^D linked to the head 3^w of the bell-crank 3^u by the new interpolator Y, which comprises a telescoping link and means to 90 lengthen and shorten it, without disconnecting. In its preferred form I provide telescoping link sections, one of which Y¹ is a rack pin-connected to the shaft arm 3^D and the other Y² comprises a head Y³, pin-connected to the bell-crank 3^u; rods Y⁴ fixed in said head; a housing Y⁵ slidable on the rods Y⁴, containing, for the rack Y¹, a bore and communicating therewith a recess for a pinion Y⁶, mounted in bearings in said 95 housing, meshed with said rack and having fixed to it a crank Y⁷ terminating in a handle Y⁸ by which the crank and pinion may be rocked to lengthen or shorten said link and rock the action shaft independently of the cam 3^f and bell-crank 3^u. Normally the crank Y⁷ is fixed relatively to the interpolator so that the latter constitutes a simple 100 link of normal length through which power is transmitted from the main to the action 10 link 11 shaft.

The normal length of the interpolator, as a link, is fixed by two pairs of nuts on the rods Y⁴, and springs Y⁹ strained between said nuts and the housing Y⁵, which construction provides a yield-point which, when the motor is automatically stopped, permits it to overrun sufficiently to assure a finished cycle. The engagement of the crank Y⁷ with the interpolator to fix its normal length comprises a socket Y¹⁰ in the action shaft arm 3^D; a pin Y¹¹ on the handle Y⁸; a spring Y¹² fast to the crank Y⁷ and engaging said handle, and adapted to hold the pin Y¹¹ in its socket; and a latching engagement Y¹³ 11 formed on collars, one fast to the pin Y¹¹, the other enveloping it but fast to the crank Y⁷. When the operator desires to interpolate hand operation, he grasps the handle Y⁸ 12 and rotates it, which causes the cam-lock 13

latching engagement Y^{13} to withdraw the pin Y^{11} from its socket and free the crank Y^7 , which, when swung, will rock the pinion Y^6 and telescope the rack Y^1 into and out of its socket, shorten and lengthen the interpolator and operate the action shaft and its belongings independently of the main shaft 3.

When the crank Y^7 is returned to normal position and the handle Y^8 rotated so that the engagement Y^{13} can function, the spring Y^{12} advances the handle and the pin Y^{11} into its socket. This interpolator is not claimed herein. It will be the subject of a separate application.

On the action shaft 3^A are fixed a number of crank sectors 3^I , one for each group of actions. Hinged to the main frame 1^B and hooked thereto, and when tilted supported by a hinged strut Z , (Figs. 17 and 18) is a table or plate 1^B which constitutes the bed plate on which is mounted the action frame 1^C , and the new selectors S and other supplemental mechanism, which will be described. The table 1^B is C-shaped, open toward the hopper 1^H to facilitate setting the selectors S , to which end the hopper cheeks 1^I are jointed as aforesaid.

In the action frame 1^C are mounted groups of tabulating actions 7, hammer actions 7^A and corresponding adders 8, all individually substantially like those of the prior invention, but differently organized in groups and with novel supplemental mechanisms as above referred to; and, suitably actuated in known modes, a platen, paper supply and ink supply or ribbon which, as embodying nothing novel, are not illustrated.

The drawings illustrate five groups, Gd , Gs , GT , (Fig. 2,) of type carriers, 7^a and 7^{aa} , the former tabulating or listing and the latter like, but supplemental and not tabulating or listing; and each group is separately mounted and has its own carrier-retractor. All the carriers and their retractors are mounted on a common pivot rod 7^f (Figs. 1 and 2) set transversely in the action frame 1^C . Each type carrier comprises a relatively movable gear segment 7^e and an adjacent type sector 7^A . Each segment 7^e has a stem 7^g , an arm 7^j with printing and limit stops 7^h and 7^i thereon, and, except the initial segment of each group, a carrying stop 7^m ; and near its heel an analyzing finger (in this case a pin) 7^k and a hook 701 by which the type carriers can be hooked back inoperative against the bar-stop nose-faces 8^o .

The type-sector 7^A comprises a lever stem 7^b which terminates beyond the pivot 7^f in spring abutments 7^c and 7^d ; a concentric type arm 7^f against the face of which the radial type bars 7^b are mounted; and a positioning limit 7^h normally held in contact

with the printing stop 7^h of the segment 7^e ; the carrier being thus distended by a spring 7^u initially strained between the hook 7^e of the sector and one on the segment. Carriers to which units are carried remain thus distended and the initial segment always; but the others are closed one tooth-space and at cycle ends their limbs 7^h approach the limit stops 7^i . Each type carrier is independently advanceable by a spring 7^u strained between the hook 7^c of the type sector and a fixed abutment. For convenience these abutments are made in the form of combs 130 with hook teeth for the springs and snap-hooks by which they themselves are hooked to a frame rod 131 .

As in the prior disclosure, each carrier-retractor 7^p is a bell-crank comprising a sleeve 7^s by which it is pivoted on the rod 7^f , cheek plates 7^r united by said sleeve, and a retraction rod 7^t to retract and time the advance of the type carriers, but not, as in the prior disclosure, to form the stroke limit and "9" stop. In the present invention the limit and "9" printing stop is the fixed shoulder 190 on the card plate 1^m above referred to.

The mode of oscillating the carrier-retractors and their respective groups of type carriers has been improved as follows:

On a pivot rod 107 , located above the carrier pivot rod 7^f (Fig. 1) and adjacent to one cheek of each retractor, I pivot a cam crank 702 containing a slotted heart cam 703 , which envelops a friction roll 700 pivoted on the retractor cheek 7^r . Said cam crank is pin-connected by a link 7^v with a crank sector 3^I of the action shaft 3^A . When said crank sector is rocked and rocks the cam crank 702 , the lobes of the heart cam permit the retractor to dwell at the beginning and end of sector-strokes, or half-cycles, so that the sectors 3^I may have time to perform their other functions while the carriers 7^a rest; and medially of such strokes the heart cam permits the advance or causes the retraction of the retractor and carriers. The just described features are not claimed.

Each action group includes a "carrying" set of hammer actions substantially like those of the prior disclosure both in structure and functions. Of such actions the drawings show a spring-struck, crank-retracted and released hammer 7^p , but no trip levers, whose motive heads cause hammer blows by functioning with cams 7^s of advanced type sectors, 7^A .

Like those of the prior disclosure and operably related with each action group, except the designating one, is an adder 8 comprising a like number of adding and carrying actions, each adapted, during carrier-retraction, to have its adding wheel 8^b engaged with the gears 7^c of a carrier 7^a

or 7^{aa} to add and set (up to "9," for subsequent printing) totals of the units counted thereby; and whenever such addition attains or exceeds ten such units, to set the 5 wheel for the proper character and carry a unit (by means of the adjacent carrier 7^a or 7^{aa} to the left as a number is read, of the next higher numerical order) to the like wheel coating therewith; the adder 8 being 10 further adapted to be engaged with the carriers during forward strokes thereof, to set totals for printing; and to "clear" or return all its adding wheels to zero position, as will be explained.

15 The drawings illustrate the adder frames 81 and of the adder action members, the forked wheel frame 8ⁿ (pivoted on the rod 83) and its wheel-pivot 8^m; the swinging, spring-retracted bar-stop 8^d with its nose, 20 and root-stops 8^e and 8^f which are spaced one tooth-angle; and the adder wheels 8^b each of which has ten teeth and, on its unit-carrying side, a carrying spur with tooth-form and radial stop faces meeting at the 25 pitch circle and the far face of the "o" tooth. The bar-stop 8^d has a totalizing abutment spur with faces like those of the wheel-spur 8^c but reversed.

30 The faces 8^e and 8^f of each bar stop 8^d are locatable in the arc of oscillation of the carrying stop 7^m of the segment 7^e of the adjacent, higher-order action; the nose face 8^e normally and non-carryingly so, to stop said segment in naught-printing position 35 and the root face 8^f carrying so by the coaction of the wheel spurs and bar-stop spurs when the addition attains ten units of the order added, to permit such segment 7^e to be retracted an additional tooth angle and 40 carry a unit to its meshed adder wheel. During tabulation and addition the adder wheels 8^b clear the segment teeth 7^e during carrier advance and are meshed therewith during carrier retraction; and to print totals 45 this order of engagement is reversed.

Mechanism 8^a to control such engagements is illustrated by its common rock shaft 8^b and organizations germane to each adder as follows: a pair of cam forks 8^c fixed to 50 said shaft 8^b and containing cam slots 8^d which engage the ends of the adder wheel pivot 8^m; a link 8^e pivoted on one cam fork 8^c and containing marginal drive slots 8^f for drive-crank pins operated from the corresponding crank sector 3ⁱ of the action 55 shaft 3^a, at each oscillation thereof, and posts 8^g which position the links 8^e. The prior disclosure is further improved as follows:

Action groups "G."

60 As illustrated in the drawings, the actions are divided into a designating or identifying group Gd, (Fig. 1,) which, at the beginning of the tabulation, is manually set 65 to be card-controlled to print once the char-

acters necessary to identify the tabulation, and thereafter to be held inactive until again manually set as aforesaid; two tabulating or listing and subtotal printing groups Gs, which may also be used for summation; and 70 two grand-total groups GT, added to or interpolated among the tabulating groups in any desired order, and each operably connected in synchronism with a tabulating group.

75

Selectors "S".

I provide a number of interchangeable open selector frames S¹⁰ (Figs. 1, 2 and 19) each formed of T-shaped plates S¹¹ (Fig. 2) 80 united by posts S¹² and thereon at their upper ends comb-like, slotted guide plates S¹³ containing guide slots S¹⁴ for the selector bars S¹; and at their lower ends other like plates S¹⁵ containing guide slots, S¹⁶. 85 Projecting from the frame S¹⁰ is a spring-abutment frame (Figs. 1 and 2) comprising slotted posts S¹⁷ and an abutment rail S¹⁸.

Fast on the posterior plate S¹¹ are C-shaped dowel frames S⁷⁰ (see particularly 90 the right of Fig. 2) and mounted therein dowel pins S⁷¹ with inward knurled heads and medial shoulder pins S⁷² and normally extended by springs S⁷³, which are strained between the pins S⁷² and the inner portion 95 of the frame S⁷⁰. In the outward limb of each frame S⁷⁰ and extending inwardly therefrom is a post S⁷⁴. When the dowel pins are retracted they may be stayed by resting their shoulder pins S⁷² on the posts 100 S⁷⁴. On the table 1^B are a transverse stop 10^s (Fig. 1) and check blocks 1^s (Fig. 2) containing holes for the dowel pins S⁷¹. The selector frame is entered between the check blocks 1^s, and pushed against the stop 105 10^s, and the dowel pins released, to enter the corresponding holes and fix the position of said frame.

110 Each selector S comprises a selector slide S¹ (Figs. 1 and 19), slidable in a slot S¹⁴ (Fig. 2) of an upper comb plate S¹³, the upper end of each slide S¹ terminating in a compensating head S²; and the lower end of each slide S¹ forming a finger S³ terminating in an adjustable tip S³⁰, adapted to 115 position the selector by contact with functioning control pins 5^h or the "9" stop 190. The control pins 5^h are equally linearly spaced, while the type bars 7^b and segment teeth 7^c are equally angularly spaced. Were 120 there no compensating connection, the equal steps of the selectors' advance and retreat would cause angularly-variable movements of the carriers 7^a and retractor 7^b and vice-versa, proportionally to the differentials of 125 the sines of successive total angles of motion thereof. To obviate this defect we provide compensating contact faces S²⁰ on either the selector heads S² or the carrier fingers 7^b.

When the carrier-selector contact line 130

moves in the tooth-angle vertically below the axis of the pivot rod 7^a; its arc departs but little from a horizontal straight line coincident with the selector's step, and the differential relatively thereto of its motion is practically *nil*; but as its successive tooth angles of motion recede and become inclined, their projections on a horizontal line shorten relatively to the like projection of the medial tooth angle and the differential relatively thereto of the motion increases. But the line of contact also moves along the compensating face S²⁰; and thereby causes a compensating motion which causes the equal steps of the selector to cause equal angular motions of the oscillating members, and vice versa. Mathematical relations determine that the compensating face S²⁰ be cylindrical. In the variant illustrated in Fig. 20 it is formed on the selector head S²⁰ and concave. In the variant illustrated in Fig. 1, it is the cylindrical surface of the analyzer pin 7^k; the contact face of the selector head may be vertical and said heads S² may extend alongside of and between segments 7^e and stay them laterally.

The selector fingers S³ of the different action groups are differently offset, as illustrated in Fig. 2. The finger tips S³⁰ (Fig. 1) are clips made of spring steel, slideable on the fingers S³ and provided with frictional setting devices consisting of little teats S³¹ on the tips which engage one or other set of sockets S³² on the finger, to set the tips in advanced or retracted position. Each selector S is independently advanceable by a spring S⁴, (Figs. 1 and 2,) strained between it and the abutment rail S¹⁸; and attached to each selector finger S³ is a guide bar S³³, which slides in a guide slot S¹⁶ of a comb plate S¹⁵. It will be noted that the bars S³³ and slots S¹⁶ are at different elevations in the several groups. In the designating group Gd these bars are plain; but in the connected actions of the tabulating and grand total groups Gs and GT they bear racks, S³⁴.

A synchronizing transmission S⁵ connects the racks S³⁴ of the selectors S of actions of like numerical orders in those pairs of tabulating groups Gs and grand total groups GT which are to work together, as shown in Figs. 1 to 5. Bearing brackets S⁵⁰ fast to the selector frame contain bearings and mount shafts S⁵¹ to each of which is fixed a pair of like gears S⁵², one meshed with the rack of a tabulating selector, the other with the rack of a grand total selector of like numerical order. As illustrated the transmissions S⁵ are at different elevations and stepped relatively to one another; the shafts S⁵¹ are equally spaced; and the gear wheels S⁵² are in diagonal series; the comb-plates S¹⁵ being offset to this end.

It may be pointed out that selector tips

S³⁰ are not necessary in the grand total action, as their only function is to afford connections for the racks S³⁴ thereof. The racks could be formed on the slides S¹ and the synchronizing transmissions located accordingly. This arrangement enables me to combine a larger number of action groups in a single machine and thereby to increase its usefulness, duty and economy.

70

75

Justifier "J."

This prevents ragged printing, so common in machines of this general character, by taking up lost motion and firmly positioning type for impressions. It comprises engagement devices on a type-positioning member of each action, preferably a rack S_o (Figs. 17 and 18) cut on the selector slide S¹ posterior to the selector frame; a positively-positioning justifying member, 80 illustrated as a transverse bar J, (Figs. 17, 18 and 19,) reciprocated in guides and adapted to engage any tooth of each justifying rack S_o to position the selector S and thereby the carrier 7^a, to justify its 90 type 7^b; and means to operate the justifying bar J, which in this case is retracted by a spring J¹ (Fig. 19) and is operated from the cams 3^x by a link-and-lever connection comprising a pair of cam-levers J² 95 medially pivoted on the main frame, held against said cams by springs J³ and at its upper ends terminating in pins J⁴; a pair of intermediate levers J⁵ medially pivoted on the table 1^b, having conformed motive arms 100 J⁶ coacting with the pins J⁴ and active arms through-connected by a cross rod J⁷ and with the justifying bar J by guide links J⁸ slidably mounted on the anterior selector-frame plate S¹¹.

105

Selector retractor.

This retracts all advanced selectors S and times their advance until they are arrested by control pins 5^h or the "9" stop 109. It 110 is a twin rocking lever (Figs. 17, 18 and 19) comprising lateral arms S⁶² medially pivoted on the cheek-plates of the main frame 1^b with their motive or lower ends mounting rollers S⁶³ held against the selector-retractor cams 3^x by springs S⁶¹, and their active or upper ends pin-and slot-connected with the retractor bar S⁶⁴ which is located transversely across the selector's path 115 by parallel guides 1^s in the main frame 120 and advanced and timed by said cams 32 and retracted by said springs S⁶¹.

120

125

Selective controller.

Originally all the action functions were 125 controllable by a settable dentent rod and push key; but experience dictated a separate key Do (Fig. 1) for initiating the one stroke of the designating group Gd and simultaneously unhooking the carriers of 130

- the grand total groups. The developed, selective controller M (Figs. 7, 8 and 11) is mounted on the table 1^B by standards and, except its key T¹ and setting knobs M³, is 5 within the action cover 177. It comprises a pivot rod M₀ and pivoted thereon a bell crank D rocked by a key D₀; a swinging dentent rod M¹ mounted by a pivot rod M¹⁰ and links M², revolute in said links and 10 swung by a key T¹; dentents, MV, M_w and MW fixed on said rod M¹; terminal setting knobs M³, and a graduated drum or dial M⁴ bearing legends readable at a gage for different control-settings of the dentents. 15 To make safe settings of the dentent rod M¹, it has a positive engagement with one link M² and a slight reciprocation to accomplish the same. A pin M⁵ is arranged on the rod M¹ and a series of properly located 20 sockets M⁶ are arranged on said link M² and a set spring M⁷ strained between said link and a collar on the rod, normally sets them in engagement but permits the rod to be freed and rotated to another setting. 25

Carrier hooks "V."

- This is a rocker organization (Figs. 1, 2, 7, 8 and 11) settable by the selective-controller dentent MV and releasable by the 30 designating-key D₀ and actuating bell-crank D to hook back the grand total group-carriers 7^a, 7^{aa} while sub-totals are being printed and to release them during tabulating and to print grand totals. 35 The rocker comprises a rock shaft V¹⁰ mounted in the action frame 1^c posterior to the carriers, and having a motive arm V¹¹ to which the link V¹ is hooked; and open frame hooks V with hook-rods V₀ to engage the hooks 701 of the carriers, and adjustable, with set screws, on the rock shaft to coact with different action groups. 40

At the face of the action frame, on a standard V⁸ I pivot a pawl V⁴ adapted to 45 engage a notch V² in said link V¹; and also a lever V⁵ fulcrumed at its middle portion one end of which is pivoted to said link which, when freed from the pawl V⁴, is retracted by a spring V⁶ to unhook the carriers. The lever V⁵, link V¹ and hook V are swung to hook back the carriers by the controller dentent MV engaging the lever V⁵. The pawl V⁴ is swung to release said members by contact of its pin V⁴⁰ by the 50 bell-crank D. 55

Selector stops "W."

These stops limit the motion of carriers 7^a, 7^{aa} to the initial tooth angle, so that they 60 can add and carry, but not tabulate. Their mode, while indirect, is effective and convenient. Anterior to and beneath the selector slides S¹ of each group (Figs. 1 and 7 to 10 inclusive) I pivot a spring-set rocker 65 stop W whose active arm mounts a bar W₀

adapted to be rocked anterior to and stop, and downwardly, to release the detracted selectors, and whose motive arm is connected by a link W¹ (except in the designating group G_d) with an actuating bell crank W². In the designating group G_d the rod W₀ extends across and stops all the selectors; but in the other action groups it functions only with the selectors of supplemental carriers 7^{aa}.

In the tabulating groups G_s the selector stops are released by dentents M_w and in the grand total groups by dentents MW, all on the dentent rod M¹. In the designating group G_d the stop crank W is linked to the bell-crank D by the link W¹, and by pressing the key D₀, which swings said crank D, the designating group stop W is retracted to free all the designating actions.

Timers or latches, "L."

The bell crank D (Fig. 9) has a lateral arm D¹ on which is formed a pin L₀ and is fixed to a cylindrical bearing D² rotatably mounted on the shaft M₀, and the bell cranks W² are fixed to the cylindrical bearings 70, rotatably mounted on the shaft M₀, on each of which bearings 70 there is formed a lateral arm 71 on which is formed a pin L₀. On the table 1^B, severally in operable relation with all save one of the crank sectors 3¹ are standards L¹ and pivoted on each and engagingly positioned by a spring L⁵, is a bell-crank L² one of whose arms terminates in a hook L³ to catch and initially release the pin L₀ of the coacting actuating crank D or W², and whose other arm carries a release pin L⁴, which near the reverse of the crank-sector 3¹, is thereby depressed to releasingly swing the bell crank L². Slidable on said standard, latched by a spring L⁸, and timed and unlatched by a pin L⁹ on the crank sector 3¹, is a latch L⁶ formed with a back-beveled latch end to engage said pin L₀ and a shoulder L⁷ to be engaged by the crank-pin L⁹.

As illustrated, (Fig. 6), the left-hand timer L serves for two action-groups, one being the designating group G_d and the other the adjacent sub-total group G_s. It has two bell cranks L², one to engage the pin L₀ of the arm D¹ of the crank D, and the other crank to engage the pin L₀ of the arm 71 formed on the crank W² of the sub-total group G_s adjacent to the designation group G_d, and the latch L⁶ of the left hand timer L has a branched latching end L^{6a}, to engage the pins L₀ of the aforesaid arms D¹ and 71. When a dentent M_w or MW of the rod M¹ swings an actuating crank its pin L₀ is depressed and engaged by a bell-crank hook L³; as a crank-sector 3¹ approaches the latch L, its pin L⁹ permits the slide latch L⁶ to advance above the pin L₀; just before the sector 3¹ reverses its motion,

it contacts with and depresses the pin L^4 of the bell crank L^2 , swings it and initially releases the actuating lever's latch-pin L_o , which rises to contact with the slide latch L^6 , now fully advanced; and as the crank sector 3^1 retires, its pin L^9 withdraws the slide latch and fully releases the actuating lever and its pin L_o , and thus times the operation of the adder 8, the rocker stop W and the hammer stop H .

No-print hammer stops "H."

It is necessary that type carries 7^a advance without causing the printing of any of their characters,—in the tabulation action groups G_s during "summation," and in the grand total groups GT while adding and carrying. For all the action groups except the designating one, I therefore provide hammer stops H (Figs. 9 and 10) set by a spring H^6 and adapted, when set to confine the hammers 7^p , and to be retracted and free them. In uprights 104 of the action frame 1^c a rocking and pivot rod 105 is mounted and the plate stops H , are pivoted thereon by their ears H_o , one of which on each stop has a shoulder, preferably on a half-hub H^1 adapted to be engaged by a pin 106 in the rod 105, which normally permits the stop H to swing; but for summation is set to engage said half-hub and set the stop H .

To independently retract the stops H , each has a posteriorly extending cam arm H^2 and suitably guided upright links H^3 pivoted on the lower arm of the corresponding bell cranks W^2 terminating above said cam arms H^2 in pins H^4 adapted to coact therewith to retract the stops H . The no-print stops H are linked up with the adders 8, for simultaneous control, in each action group. Each actuating bell crank W^2 is connected by the post 8^H with the cam forks 8^c whose cam slots 8^D position the set of adder wheels 8^b and release carryingly-positioned bar stops 8^d . Therefore the same control motion that causes the no-print stops H to release the hammers 7^p for printing also leaves the adder wheels 8^b meshed with the teeth 7^e of the retracted carriers, to printingly position type thereof for printing by the hammers. The same motion engages the latch pins L_o of said crank W^2 with adjacent timer latches L ; and at the end of the total printing cycle the crank sectors 3^1 time the release thereof; and springs W^7 strained from the lower arms of the bell cranks W^2 to the action frame lift the bell cranks, vertical links H^8 , and posts 8^H to confine supplemental actions 7^{aa} . The rod 105 has at one end a knob or handle; a pointer 114 and no-print dial 115 are ar-

ranged on the rod and case, to read the rod's setting.

Column-blanker or individual hammer stop.

To blank a particular column by staying its hammer 7^p , I mount a spline rod 109 (Figs. 9 and 10) in extensions 108 of the action frame, spline on said rod a post 110 and to it pivot a blunker-bar 111, fixable in operative and non-operative positions by engagement of sockets with a tongue 112, advanced by a spring 113.

Operation.

When tabulation or summarizing of a card sequences is begun, it is desirable to print designating or identifying characters, (which in most tabulations need not be repeated), and it is necessary that actually tabulating actions and therewith connected selectors of the grand total groups GT be free to make their full strokes, save as positioned by functioning control pins 5^h ; and that the supplemental carriers be able to move one tooth-angle in order to add and carry the totals.

Sub-totals are of frequent occurrence; but there can be only one grand total; and sub and grand totals may be printed either simultaneously or successively, the dentents Mw and MW being arranged accordingly. Further, it might be desired to summarize with the tabulation action groups G_s without carrying the totals thereof into the grand-total actions.

The above described organization accomplishes all the above results. The selectors S can advance when the carriers 7^a , 7^{aa} , are hooked back; but, because each selector acts as a stop for its carrier, retracted selectors confine and limit the oscillation of their carriers to the initial tooth angle, necessary to cause them to add and carry.

Initial cycle.

Pressing the designating key D simultaneously swings the bell crank D , the designating group rocker stop W , to free the designating actions (which so remains during the initial cycle only); and the hooks V to unhook the grand total carriers. When so unhooked the supplemental carriers 7^{aa} and selectors of such grand total carriers are normally limited by the coaction of their rocker stops W and selector slides S^1 , to the initial tooth-angle of motion. The tabulating actions tabulate or summarize accordingly as their no-print stops H are retracted or set by the rod 105 and pins 106; but the supplemental actions can only add and carry for totals when freed by retracting their rocker stops W .

When the designating key is pressed the lever D engages its latch pin L_o with the hook L^3 of the adjacent timer latch L ; and

at the close of the first cycle the crank sector 3¹ operates the timer latch L to release said bell crank and set the rocker stop W linked thereto to stop the designating actions.

- 5 During tabulation or summarizing the synchronizing transmission S⁵ synchronizes connected actions of tabulating and grand total groups, G₈ and GT. Summarizing is 10 done by timing the rod 105 so that pins 106 thereof set hammer stops H and no characters can be printed, notwithstanding that all the topical records are analyzed, and added and carried in the adders 8.
- 15 At proper times sub and grand totals can be printed as follows:

To print totals.

- 20 Where totals of any kind are to be printed a setting card punched at all the naughts, and a stop card are interpolated in or added to the card sequence. When, in tabulating or summarizing, the setting card is reached, all the "0" analyzing pins 5^h are extended 25 and all the carriers 7^a, 7^{aa} are alined and similarly meshed with the adders; but no character is printed because no carrier cam 7^s becomes operative. The machine is now ready to set and print totals.
- 30 At the beginning of the next cycle the stop card functions to stop all the analyzing pins 5^h and permit the stop pin 6^u to cause the work-suspending mechanism 6 to stop the machine. The pin box 5, feed mechanism 4 and card C rest until after the total or totals are printed, by means of the interpolator Y.

To print sub-totals, firstly, the dentent rod M¹ is turned to set the dentent MV, and 40 swung to hook back the grand total carriers, to prevent them from spoiling the totals already set in the grand total adders; secondly, said rod is turned to set the dentents Mw (which affect the tabulating groups G₈ 45 only) and swung to swing their actuating cranks W², engage them by their latch pins L₀ with the timers L, depress the connected rocker stops W to free the supplemental actions 7^{aa}, pull down the posts 8^H and links 50 8^E, and the links H³ to retract the hammer stops H and free the hammers 7^D; thirdly, the interpolator handle Y^s is grasped and given a quarter turn to withdraw the pin Y¹¹ from its socket and free the crank Y⁷, 55 which is thereupon swung out and back, rocks the connected pinion Y⁶, telescopes and again extends the interpolator link, rocks the action shaft 3^A, prints the subtotal, operates the timers L and restores the 60 machine to normal relations.

To print grand totals, either simultaneously with or subsequent to the printing of the final sub-totals; the dentent rod M¹ is timed to set the cams MW and depress the 65 grand total groups actuating cranks W²;

after which the operation is like taking sub-totals. If the final sub-total and the grand total must be printed separately, hook-organizations V to V⁶ inclusive and dentents, MV, for the tabulating actions, must be 70 added to the machine.

Clearing.

When a total is printed, all the function adder wheels are in zero position; and if the 75 machine thereafter functions normally, such adders are cleared and begin to add and carry new sums. They can, however, be made to continue to carry and add new members to the just-printed sub-, or grand- total. 80

The total-printing cycle begins when the carriers are retracted and while the adder wheels remain engaged therewith subsequent to a just completed carrier-setting cycle controlled by a card punched at all the naughts. 85

In analyzing cycles the first (or subsequent) function is to separate the adders from the carriers, during the dwell and prior to the advance of the latter. But to print totals the adders must remain engaged 90 with the carriers throughout the first half of the cycle and carrier-advance. To that end the actuating crank W² now depresses the link 8^E, so that the link 8^E will not be reciprocated to affect the cams 8^D and thereby the position of the adder wheels; and advancing carriers turn the adder wheels backward and are printingly positioned by them when their spurs contact with the bar-stop spurs. At this instant the adder wheels 8^b 100 are all set at zero; and "clearing" is effected by separating them from the carriers subsequent to printing but before the latter move.

In the normal total-printing cycle, at about this period, latches L free the actuating cranks, W², whose spring-actuated retraction lifts the posts 8^H and links 8^E, to permit the links 8^E to be reciprocated to swing the cam forks 8^C and cause the cams 8^D to retract the adder wheels 8^b and effect 110 "clearing." But obviously if the links 8^E were held motionless, the adder wheels 8^b and carrier teeth 7^C would remain engaged and the latter would restore the former to the conditions existing at the beginning of 115 the cycle, that is, would reset them to the totals just printed. This is readily accomplished by holding the selective controller advanced with its dentents Mw or MW in contact with and positioning the actuating 120 levers W².

Printing grand totals and sub-totals simultaneously with one swing of the dentent rod M, is made possible by providing two sets of angularly-separated contacts on the dentent Mw, one set alined with the dentents MW. When printing totals there are no functioning pins 5^h to stop selectors S; consequently they follow the retractors 7^D to the 125 "9" stops, 109, and the tabulating and grand 130

total carriers are set by their respective adders 8.

I claim:

1. In a tabulating and printing machine for tabulating and printing items, sub-totals and grand totals, the combination of control members; tabulating and printing mechanism adapted to print items and to accumulate said items and to print sub-totals thereof; and a grand total accumulating and printing mechanism operatively connected with the tabulating and printing mechanism and adapted to automatically print grand-totals of said items synchronously with the printing of said sub-totals. 15
2. In a tabulating and printing machine for tabulating and printing items, sub-totals and grand-totals, the combination of control members; tabulating and printing mechanism adapted to print items and to accumulate said items and to print sub-totals thereof; and a grand - total accumulating and printing mechanism operatively connected with the tabulating and printing mechanism 20 and adapted to automatically print grand-totals of said items synchronously with the printing of said sub-totals on the same sheet with said sub-totals. 25
3. In a tabulating and printing machine for tabulating and printing items, sub-totals and grand-totals, the combination of control members; tabulating and printing mechanism adapted to print items and to accumulate said items and to print sub-totals thereof in the same column; and a grand total accumulating and printing mechanism operatively connected with the tabulating and printing mechanism and adapted to automatically print grand - totals of said items 35 synchronously with the printing of said sub-totals to one side of said sub-totals. 40
4. In a tabulating and printing machine for printing individual items, sub-totals and grand-totals of records, the combination of control members; selectors adapted to be positioned by said control members; tabulating and printing mechanisms positioned by said selectors and adapted to print items and sub-totals; totalizing mechanisms adapted to carry and print grand-totals; selector bars movably supporting said selectors; and synchronizing mechanisms connecting the bars of the selectors of like numerical order in the sub-total and grand-total groups. 45
5. In a tabulating and printing machine for printing individual items, sub-totals and grand-totals of records, the combination of control members; selectors adapted to be positioned by said control members; tabulating and printing mechanisms positioned by said selectors and adapted to print items and sub-totals; totalizing mechanisms adapted to carry and print grand-totals; selector bars movably supporting said selectors and provided with racks; and synchronizing mech- 50
- anisms connecting the racks of the selectors of like numerical orders in those pairs of grand-total and sub-total groups that are to be worked together. 55
6. In a tabulating and printing machine for printing individual items, sub-totals and grand-totals of records, the combination of control members; selectors adapted to be positioned by said control members; tabulating and printing mechanisms positioned by said selectors and adapted to print items and sub-totals; totalizing mechanisms adapted to carry and print grand-totals; selector bars movably supporting said selectors and provided with racks; and synchronizing mech- 60 anisms connecting the racks of the selectors of like numerical orders in those pairs of grand-total and sub-total groups that are to be worked together. 65
7. In a tabulating and printing machine for printing individual items, sub-totals and grand-totals of records, the combination of control members; selectors adapted to be positioned by said control members; sub-total and tabulating action groups and grand-total action groups comprising type carriers positioned by the selectors, some of which carriers are supplemental carriers; means associated with the carriers to cause them to add and print sub-totals and grand-totals; selector bars movably supporting said selectors and provided with racks; and synchronizing mechanisms connecting the racks of the selectors of like numerical orders in those pairs of grand - total and sub - total groups that are to be worked together. 75
8. In a tabulating and printing machine for printing individual items, sub-totals and grand-totals of records, the combination of control members, selectors adapted to be positioned by said control members; sub-total and tabulating action groups and grand-total action groups comprising type carriers positioned by the selectors, some of which carriers are supplemental carriers; means associated with the carriers to cause them to add and print sub-totals and grand-totals; selector bars movably supporting said selectors and provided with racks; a justifying bar adapted to engage certain of said racks to justify the type of said groups; guides in which said bar is reciprocated; cams on the drive shaft of the machine; levers medially fulcrumed on the frame of the machine and spring pressed at one end on said cams; and intermediate levers fulcrumed medially on said frame and having their motive ends engaging the active ends of said first named levers and having their active ends operatively connected to said bar. 80
9. In a tabulating and printing machine for printing individual items, sub-totals and grand-totals of records, the combination of control members; tabulating and printing 85

mechanism comprising selectors adapted to be positioned by said control members; selector stops adapted to engage and stop certain of said selectors; means for at will 5 bringing said stops into action; and timing mechanism adapted to release said means after the stops have performed their functions.

10. In a tabulating and printing machine 10 for printing individual items, sub-totals and grand-totals of records, the combination of control members; selectors adapted to be positioned by said control members; type carriers comprising elements adapted to be 15 positioned by the selectors; crank sectors corresponding to the type-carriers respectively; selector stops adapted to engage and stop certain of the selectors; actuating cranks connected to said stops; and means 20 for actuating said actuating cranks.

11. In a tabulating and printing machine for printing individual items, sub-totals and grand-totals of records, the combination of control members; selectors adapted to be 25 positioned by said control members; type carriers comprising elements adapted to be positioned by the selectors; crank sectors corresponding to the type-carriers respectively; selector stops adapted to engage and 30 stop certain of the selectors; actuating cranks connected to said stops; means for actuating said actuating cranks; and latch and timer mechanisms actuated by said crank sectors for holding said actuating 35 cranks in actuated position and releasing them after they have performed their functions.

12. In a tabulating and printing machine for printing individual items, sub-totals and 40 grand-totals of records, the combination of control members; selectors adapted to be positioned by said control members; type carriers adapted to be positioned by said 45 selectors; selector bars movably supporting said selectors; crank sectors corresponding to the type-carriers respectively; selector stops adapted to engage and stop certain of 50 said selector bars; actuating cranks connected to said selector stops; and means for actuating said cranks.

13. In a tabulating and printing machine for printing individual items, sub-totals and grand-totals of records, the combination of control members; selectors adapted to be 55 positioned by said control members; type carriers adapted to be positioned by said selectors; selector bars movably supporting said selectors; crank sectors corresponding to the type-carriers respectively; selector 60 stops adapted to engage and stop certain of said selector bars; actuating cranks connected to said selector stops; means for actuating said cranks; and latch and timer mechanisms actuated by said crank sectors 65 for holding said actuating cranks in actu-

ated position and releasing them after they have performed their functions.

14. In a tabulating and printing machine for printing individual items, sub-totals and grand-totals of records, the combination of 70 control members; selectors adapted to be positioned by said control members; designating action groups, tabulating and sub-total action groups and grand-total action groups comprising type carriers adapted to be positioned by said selectors; means for bringing about printing by the type of said carriers; and means for stopping the selectors of the designating action groups when printing of grand-totals or sub-totals takes place. 75

15. In a tabulating and printing machine for printing individual items, sub-totals and grand-totals of records, the combination of control members; action groups comprising 80 designating type carriers positioned by said control members; carrier hooks for hooking back certain of type carriers; means for operating said hooks; pawls for holding them in operative position; and means adapted to release said pawls. 85

16. In a tabulating and printing machine for printing individual items, sub-totals and grand-totals of records, the combination of control members; designating printing action groups, tabulating and sub-total printing action groups and grand-total printing action groups, said total groups adapted to print sub-totals and grand-totals simultaneously, said groups being controlled 90 by said control members; means for normally stopping the printing action of the grand-total group; and means for suspending the action of said stopping means. 95

17. In a tabulating and printing machine for printing individual items, sub-totals and grand-totals of records, the combination of control members, designating printing action groups, tabulating and sub-total printing action groups and grand-total printing action groups, said total groups 100 adapted to print sub-totals and grand-totals simultaneously, said groups being controlled by said control members; means normally limiting the movements of said grand-total groups; and means for suspending 115 the action of said limiting means when printing grand-totals. 110

18. In a tabulating and printing machine for printing individual items, sub-totals and grand-totals of records, the combination of control members, designating printing action groups, tabulating and sub-total printing action groups and grand-total printing action groups, said total groups adapted to print sub-totals and grand-totals simultaneously, said groups being controlled by said control members; means normally limiting the movements of said grand-total groups; means for suspending the action of said limiting means when printing grand-totals; 120 125 130

and means for timing the action of the suspending means and suspending its action when its function is accomplished.

19. In a tabulating and printing machine for printing individual items, sub-totals and grand-totals of records, the combination of control members; selectors adapted to be positioned by the control members; designating action groups; sub-total action groups and grand-total action groups comprising type carriers adapted to be positioned by the selectors; synchronizing means connecting the respective selectors of a sub-total group with selectors of like numerical order in a grand-total group; crank sectors corresponding to respective type carriers; selector stops adapted to stop certain of the selectors; hammers for causing the type of the type carriers to print; hammer stops for holding said hammers inoperative; means for holding back out of printing position certain of the type carriers; means for holding the type-carrier-holding means in operative position; adding mechanisms to be moved by the crank sectors to engage and disengage the type carriers; actuating devices adapted when actuated to cause the adding mechanism to remain in engagement with said carriers and to cause to become operative said selector stops, said hammer stops and to cause to become operative the means for holding back the type carriers; a selective controller for at will actuating certain of said actuating devices; and latch and timer mechanisms actuated by the crank sectors for holding the actuating devices in actuated position and releasing them after the parts actuated thereby have performed their functions.

40 20. In a tabulating and printing machine for printing individual items, sub-totals and grand-totals of records, the combination of control members; selectors adapted to be positioned by the control members; sub-total action groups and grand-total action groups comprising type carriers adapted to be positioned by the selectors; hammers for causing the type of the type carriers to print; hammer stops for holding said hammers inoperative; actuating devices adapted when actuated to cause said hammer stops to become inoperative; and means for operating the actuating devices, said hammer stops comprising a pivot rod, stop plates mounted thereon and provided with a shoulder, a pin in said rod adapted to engage said shoulder and normally permitting the stop plate to swing, an arm on the stop plate and links connecting said arms with said actuating devices.

65 21. In a tabulating and printing machine for printing individual items, sub-totals and grand-totals of records, the combination of control members; selectors adapted to be positioned by the control members; sub-total

action groups and grand-total action groups comprising type carriers adapted to be positioned by the selectors; crank sectors corresponding to respective type carriers; hammers for causing the type of the type carriers to print; hammer stops for holding said hammers inoperative; adding mechanisms to be moved by the crank sectors to engage and disengage the type carriers; actuating devices adapted when actuated to cause said adding mechanism to remain in engagement with the carriers; and latch and timer mechanisms actuated by the crank sectors for holding the actuating devices in actuated position and releasing them after the parts actuated thereby have performed their functions.

22. In a tabulating and printing machine for printing individual items, sub-totals and grand-totals of records, the combination of control members; selectors adapted to be positioned by the control members; sub-total action groups and grand-total action groups comprising type carriers adapted to be positioned by the selectors; crank sectors corresponding to respective type carriers; hammers for causing the type of the type carriers to print; hammer stops for holding said hammers inoperative; adding mechanisms to be moved by the crank sectors to engage and disengage the type carriers; actuating devices adapted when actuated to cause said adding mechanism to remain in engagement with the carriers; and latch and timer mechanisms actuated by the crank sectors for holding the actuating devices in actuated position and releasing them after the parts actuated thereby have performed their functions, said latch and timer mechanisms comprising a spring pressed bell crank having a hooked end adapted to engage over and hold in actuated position the actuating device and adapted to be engaged and released by said sector, and a spring pressed sliding latch adapted to engage and hold said actuating device when thus released by said bell crank, and a pin on the crank sector adapted to engage the latch and to time or effect the release by the latch of the actuating mechanism.

23. In a tabulating and printing machine for printing individual items, sub-totals and grand-totals of records, the combination of control members; selectors adapted to be positioned by the control members; designating action groups; sub-total action groups and grand-total action groups comprising type carriers adapted to be positioned by the selectors; crank sectors corresponding to respective type carriers; synchronizing means connecting the respective selectors of a sub-total group with selectors of like numerical order in a grand-total group; hammers for causing the type of the type carriers to print; hammer stops

for holding said hammers inoperative; means for holding back out of printing position certain of the type carriers; means for holding the type-carrier holding means in operative position; adding mechanisms to be moved by the crank sectors to engage and disengage the type carriers; actuating devices adapted when actuated to cause the adding mechanism to remain in engagement with said carriers and to cause to become operative said selector stops, said hammer stops and to cause to become operative the means for holding back the type carriers; a selective controller for at will actuating certain of said actuating devices; and comprising a plurality of links pivoted at one end to the machine frame, a pivot rod rotatably mounted in said links, a key adapted to press against one of said links to move said rod laterally, and detents on the rod projecting therefrom in different directions and adapted to press against said actuating devices.

24. In a tabulating and printing machine for printing individual items, sub-totals and grand-totals of records, the combination of control members; selectors adapted to be positioned by the control members; designating action groups; sub-total action groups and grand-total action groups comprising type carriers adapted to be positioned by the selectors; crank sectors corresponding to respective type carriers; synchronizing means connecting the respective selectors of a sub-total group with selectors of like numerical order in a grand-total group; hammers for causing the type of the type carriers to print; hammer stops for holding said hammers inoperative; means for holding back out of printing position certain of the type carriers; means for holding the type-carrier-holding means in operative position; adding mechanisms to be moved by the crank sectors to engage and disengage the type carriers; actuating devices adapted when actuated to cause the adding mechanism to remain in engagement with said carriers and to cause to become operative said selector stops, said hammer stops and to cause to become operative the means for holding back the type carriers; a selective controller for at will actuating certain of said actuating devices; and comprising a plurality of links pivoted at one end to the machine frame, a pivot rod rotatably mounted in said links, a key adapted to press against one of said links to move said rod laterally, detents on the rod projecting therefrom in different directions and adapted to press against said actuating devices; and means for holding said rod positioned in different positions of rotation, and a graduated drum on said rod and having legends for controlling the different settings 65 of the detents.

25. In a tabulating and printing machine for printing individual items, sub-totals and grand-totals of records, the combination of control members; selectors adapted to be positioned by said control members; sub-total and tabulating action groups and grand-total action groups comprising type carriers positioned by the selectors, some of which carriers are supplemental carriers; selector bars movably supporting said selectors; crank sectors corresponding to the type carriers respectively; adding and carrying mechanisms adapted to be moved into and out of engagement with said action groups, except the designating group, by the movement of said sectors; selector stops adapted to engage and stop the selector bars of certain of the selectors including those coöperating with the designating carriers; hammers for causing the type of the type carriers to print; hammer stops for stopping the action of said hammers of the grand-total groups; actuating devices to which said selector stops and said hammer stops are connected and by which they are moved to be rendered inoperative when said devices are actuated; means actuating said devices; means for holding the adding and carrying mechanisms in engagement with the type carriers on the actuation of said actuating devices; and timers actuated by the crank sectors for holding said actuating devices in actuated position and releasing them after said stops have performed and adding and carrying mechanisms have performed their functions.

26. In a tabulating and printing machine for printing individual items, sub-totals and grand-totals of records, the combination of control members; selectors adapted to be positioned by said control members; designating action groups, tabulating and sub-total action groups and grand-total action groups comprising type carriers adapted to be positioned by said selectors; selector bars movably supporting said selectors; synchronizing transmissions connecting the bars of the selectors of like numerical order in the sub-total and grand-total groups; crank sectors corresponding to the type-carriers respectively; selector stops adapted to engage and stop certain of said selector bars; hammers for causing the type of the type carriers to print; hammer stops for rendering the hammers inoperative; carrier hooks for hooking back certain of the type carriers; means for operating said hooks; pawls for holding said hooks in operative position; adders adapted to engage said type carriers; shifting means operated by the crank sectors disengaging the adders for the type carriers; positioning means for rendering said shifting means inoperative; actuating cranks connected to said selector stops, said hammer stops and said positioning means for render- 130

ing said pawls, stops and positioning means operative when said actuating cranks are actuated; a selective controller for at will selecting and actuating certain of said 5 cranks; and latch and timer mechanisms actuated by said crank sectors for holding said actuating cranks in actuated position and releasing them after they have performed their functions.

10 27. In a tabulating and printing machine for printing individual items, sub-totals and grand-totals of records, the combination of control members; selectors adapted to be positioned by said control members; designating action groups; sub-total and tabulating action groups and grand-total action groups comprising type carriers positioned by the selectors, some of which carriers are supplemental carriers; selector bars movably supporting said selectors; crank sectors corresponding to the type carriers respectively; carrier hooks for hooking back certain of type carriers; means for operating said hooks; pawls for holding them in operative 20 position; actuating cranks by which said pawls are moved to render them inoperative; and means for actuating said cranks.

28. In a tabulating and printing machine for printing individual items, sub-totals and 30 grand-totals of records, the combination of control members; selectors adapted to be positioned by said control members; designating action groups; sub-total and tabulating action groups and grand-total action groups comprising type carriers positioned by the 35 selectors, some of which carriers are supplemental carriers; selector bars secured to said selectors; crank sectors corresponding to the type carriers respectively; carrier hooks for 40 hooking back certain of type carriers; means for operating said hooks; pawls for holding them in operative position; actuating cranks by which said pawls are moved to render them inoperative; and latch and timer mechanisms actuated by said crank sectors for 45 holding said actuating cranks in actuated positions and releasing them after they have served their functions.

29. In a tabulating - printing machine of 50 the class described, for printing individual items, sub-totals and grand-totals of records, control members for reproducing such records, tabulating-printing mechanism adapted to be positioned by contact with said control members to tabulate and to print, and controllable to print and not to print while otherwise operating; the combination therewith of a timer operably connected with such mechanisms, manually settable to cause 55 60 connected mechanisms to print once in a cycle and operable therewith during the remainder of such cycle to non-printingly control said actions.

30. In a tabulating - printing machine of 65 the class described for printing records com-

prising series of reciprocating control pins for reproducing such records; an action shaft; means to reciprocate said pins and rock said action shaft; operably connected with said action shaft a series of mechanisms 70 each comprising a movable type carrier and operably related therewith a hammer action and an adding action,—each of said type carriers operably mounting a sequence of type and a series of gear teeth and 75 adapted to be positioned and to printingly position type in consonance with record-reproducing control-pins,—said hammer action operable by an advance of said carriers to strike printingly-positioned type there- 80 of,—and said adding actions assembled in carrying series to constitute adders and each having an adding wheel adapted to be separated from and meshed with a carrier to be controlled thereby to add and carry and to 85 control the same to set totals for printing; and manually settable adder-control means adapted to mesh and separate the adders and carriers; the combination therewith of a hammer-stop settable to prevent and to 90 permit the stroke of action-released hammers aforesaid; a shifting member operably connected with and advanceable to set said hammer stop and adder control means, and a latch mechanism operably connected with 95 said action shaft and adapted at the beginning of a cycle to engage and position said hammer stop and adder-control means and later in said cycle to be operated from said action shaft to release said members. 100

31. In a tabulating - printing machine of the class described for printing records comprising series of reciprocating control pins for reproducing such records; an action shaft; means to reciprocate said pins and rock said action shaft; operably connected with said action shaft, series of mechanisms each comprising a movable type carrier and operably related therewith a hammer action and an adding action,—each of said type carriers operably mounting a sequence of type and a series of gear teeth and adapted to be positioned and to printingly position type in consonance with record-reproducing control-pins,—said hammer action operable by 115 an advance of said carrier to strike printingly positioned type thereof,—and said adding actions assembled in carrying series to constitute adders and each having an adding wheel adapted to be separated from and meshed with a carrier to be controlled thereby to add and carry and to control the same to set totals for printing; and manually settable adder-control means adapted to mesh and separate the adders and carriers; the combination therewith of stops settable to prevent and to permit the operation of specific action members; shift mechanism operably connected with and movable to set said stops and adder-control; and timing 120 125 130

mechanism adapted, at succeeding cycle-periods, to engage said adder-control and stops, when set and to be operated from said action shaft to time the retraction of said 5 members.

32. In a tabulating and printing machine for printing individual items, sub-totals and grand-totals of records, the combination of control members; selectors adapted to be positioned by said control members; designating action groups; sub-total and tabulating action groups and grand-total action groups comprising type carriers positioned by the selectors, some of which carriers are supplemental carriers; selector bars movably supporting said selectors and provided with racks; a justifying bar adapted to engage certain of said racks to justify the type of said groups; synchronizing mechanisms connecting the racks of the selectors of like numerical orders in those pairs of grand-total and sub-total groups that are to be worked together; crank sectors corresponding to the type carriers respectively; adding and carrying mechanisms adapted to be moved into and out of engagement with said action groups, except the designating group, by the movement of said sectors; selector stops

adapted to engage and stop the selector bars of certain of the selectors including those 30 coöperating with the designating carriers; hammers for causing the type of the type carriers to print; hammer stops for stopping the action of said hammers of the grand total groups; carrier hooks for hooking back 35 certain of type carriers; means for operating said hooks; pawls for holding them in operative position; actuating cranks to which said selector stops and said hammer stops are connected and by which the stops 40 and said pawls are moved to render them inoperative; a selective controller for actuating said actuating cranks; means for holding said adding and carrying mechanisms in engagement with the type carriers on the 45 actuation of said cranks; latch and timer mechanisms actuated by said crank sectors for holding said actuating cranks in actuated positions and releasing them after they have their functions; and means for at will 50 rendering inoperative said hammer stops.

JAMES POWERS.
